UNITED STATES PATENT OFFICE.

HENRY AUGUSTE CHALVIN, OF NEW YORK, N. Y., ASSIGNOR TO COOK & BERNHEIMER, OF SAME PLACE.

BOTTLE.

SPECIFICATION forming part of Letters Patent No. 308,950, dated December 9, 1884.

Application filed June 26, 1884. (No model.)

To all whom it may concern:

Be it known that I, HENRY AUGUSTE CHALVIN, a citizen of the United States, residing in the city of New York, county of New York, and State of New York, have invented a certain new and useful improvement in bottling liquids, especially cordials or liquids containing a large percentage of sugar, of which the following is a specification.

- 10 The object of my invention is to place within the bottle containing the cordial or liquor a sprig or spray of a tree or shrub, or a bunch of grasses, and so attach or secure the same that it assumes the position and appearance 15 of a small tree, upon which the crystals of sugar in the liquid will be deposited, so as to have the appearance of snow or frost.
- 20 In the drawing I have shown a side view of a bottle with a portion of the side removed, 20 for the purpose of showing the arrangement of the tree within it. The manner in which this sprig is placed within the bottle is as follows: Before the bottle is filled a hole is drilled through the glass composing it, preferably at the center of its bottom, as at *a*. A sprig or spray of a tree or shrub is then selected, or a number of sprigs, or preferably grasses, may be bunched together and tied. 25 In selecting this sprig or bunch of sprigs or grasses I prefer to use something supposed to have medicinal properties, although this is not essential, providing that the character is such as not to injure the contents of the bottle when filled, or give it a bad flavor. For this 30 purpose I have generally used some of the grasses called by botanists *Festuca*. The stem of the sprig is slightly sharpened, so as to make it find ready entrance into the hole drilled through the glass of the bottle. Then 35 40 a wire is attached to the stem, sufficiently long to extend into the mouth of the bottle, and out through the hole drilled through the glass. By passing this wire in that way through the bottle and grasping the end which projects 45 beyond the hole drilled in the glass the sprig is drawn down through the neck of the bottle and through the body thereof until its

stem, to which the wire is attached, is drawn into the hole drilled through the glass. If drawn tightly into this hole the stem of the sprig will form a plug to prevent the escape of the liquid, and at the same time will hold the tree firm in any position desired, no matter what may be the position in which the bottle is held.

The position in which I prefer to secure the sprig or spray is shown in the drawing, because then it presents the appearance of a small tree standing at the center of the bottom of the bottle. In case the stem does not fully close the hole drilled in the bottle, a plug may be inserted from the outside for that purpose, or a plastic material may be used. After the sprig has been placed in the bottle as above described, the bottle is then filled 65 with some liquor which abounds in sugar—as, for instance, “rock and rye” or a cordial—and which is in a heated condition, so as to keep the sugar crystals in solution while hot. The liquor at the time the bottle is filled should 70 be in such condition that the sugar is practically all in solution or suspension. After the bottle has been allowed to stand for some time the liquor will become cool and the crystals of sugar will be deposited, some of them falling 75 to the bottom around the stem of the sprig, as at *b*, and there forming a bed which has the appearance of snow. Others will deposit 80 themselves upon the leaves or twigs of the sprig, and give it the appearance of a tree covered with frost or snow. In this condition the bottle of wine may be sold as an article of manufacture, and the sprig within it greatly adds to its attractiveness and salability.

I claim—

As an article of manufacture, a bottle containing a sprig secured within it by having its end inserted through a hole in the glass, substantially as described.

HENRY AUGUSTE CHALVIN.
